UNITED STATES PATENT OFFICE.

CONSTANTINE ZELENAY, OF TVER, RUSSIA.

MACHINE FOR EXCAVATING TURF.

1,113,277.

Specification of Letters Patent.

Patented Oct. 13, 1914.

Application filed April 26, 1912. Serial No. 693,419.

To all whom it may concern:

Be it known that I, CONSTANTINE ZELENAY, subject of the Emperor of Russia, residing at Tver, Russia, have invented new and useful Improvements in Machines for Excavating Turf, of which the following is a specification.

This invention has for its object to provide an improved combination machine for cutting peat from a drained peat bog and treating the cut peat.

With this object the machine is mounted on a carriage adapted to travel on a railway along the peat trench while the cutting devices can be moved sidewise to a certain extent.

The improved machine consists substantially of a tubular cutting apparatus provided at its lower end with an apparatus for loosening and cutting up the peat which is lifted by a worm conveyer and conveyed to a mixing apparatus.

One construction of the improved machine is illustrated by way of example in the accompanying drawings in which:—

Figure 1 is an end elevation of the machine. Fig. 2 is an elevation of the cutting apparatus partly in section. Fig. 3 is a plan of the improved machine. Fig. 4 is a front elevation of the improved machine. Figs. 5 and 6 are respectively sectional views on the lines A—A and B—B of Fig. 8. Figs. 7 and 8 are respectively a bottom view and a plan of the apparatus for loosening the peat, and Fig. 9 is a sectional view on the line C—C of Fig. 8.

The entire machine (Figs. 1, 3 and 4) is mounted on a carriage 1 which is moved on a railway 2 along the peat trench by means of a windlass 3 and two chain drives 4 and 5. This carriage carries a railway composed of two cross-beams 6 along which the movable framing 7 moves which carries the actual peat cutting apparatus and is moved by hand by means of the operating mechanism 8. For the purpose of maintaining the equilibrium of the machine during the travel of the frame 7, the latter carries a traveling counterweight 50 which is shifted by means of ropes 51 passing around the guide pulleys 52 and 53 and attached to the framing and counterweight in such a manner that the said framing and counterweight are simultaneously caused to move toward or away from the carriage 1.

The peat cutting apparatus (Figs. 1, 2 and

3) consists of the loosening device 9 and the screw conveyer 11 arranged inside the tube 10. The tube 10 is fixed to the plate 12 which also serves to carry the electric motor 13, the footstep bearings 14 and 15 of the loosening device and screw, the gear etc. The plate 12 is suspended by means of a rope 19 and pulleys 16 and 17 and is adapted to be drawn up and down together with the tube 10 and the devices mounted on it by means of the windlass 18.

The peat is cut from the peat bog in rows in the longitudinal and transverse directions. When a transverse row has been cut, the machine is shifted by means of the windlass 3 through an equal distance to the diameter of the tube. The length of the tube 10 depends on the depth of the bed of peat being cut. Inside the tube 10 (Fig. 2) is a shaft 20 on which the loosening device 9 is fixed. The shaft 20 is surrounded by a second hollow shaft 21 which is provided with a conveyer screw 11. To the lower end of the tube 10 is fixed a cross-piece 22 (Fig. 5) in which are provided three ball bearings 23, 24 and 25 for the shafts 20 and 21.

The loosening device 9 consists of a truncated conical member containing two diametrically staggered partitions 26 with screw or helical surfaces, or their equivalent, two helical apertures or passages 27. The lower edges of the apertures 27 are provided with broad flat cutters 28 which cut the peat or cut spirally into hard bodies such as old tree stumps. The shaft 20 with the loosening device is rotated at a high speed so that the cut peat is caused by its momentum to enter the loosening device 9 and pass upward along the passage.

In order that the cut peat shall be effectively caught the underside of the loosening device is made conical so that any pieces of peat flying off under centrifugal action will be yet caught by the passages 27. For this purpose also the cutting edge of the cutter 28 is set at an angle to the radius. In order to prevent wear of the upper edges of the cross-partitions 26, the upper surface of the loosening device 9 is covered with a correspondingly recessed plate 29 of hardened steel so that this plate forms together with the arms of the cross-piece 22 a second cutting device. The outer edges of the cutters 28 extend beyond the lower diameter of the loosening device for the purpose of preventing the loosening device from being braked.

by the peat and of facilitating the lifting out of the cutting apparatus.

In order to facilitate cutting into the peat bed the loosening device 9 is provided at its lower part with a gradually diminishing drill 47 the greatest diameter of which is equal to the diameter of the hub 48 of the loosening device. Further triangular cutters 49 are fixed to the lower edge of the same in front of the cutters 28, for the purpose of preventing the accumulation of peat, stones or splinters at this part.

In the drawings (Figs. 5 to 8) a loosening device is shown by way of example with two passages, but the number of such passages may be increased to suit the section of the loosening device and the particular nature of the kind of peat being cut. The loosened peat moving up in the tube 10 is then received by the conveyer screw 11 fixed on the shaft 21 and is conveyed to the top where it falls through the enlarged opening 54 of the tube 10 into a chute 30 and thence to a conveyer belt 31. The shafts 20 and 21 receive their motion by means of toothed wheels from the electric motor 13. The peat is delivered by the conveyer belt 31 into a suitable mixing apparatus which serves to mix it intimately.

Having now particularly described and ascertained the nature of my said invention and in what manner the same is to be performed, I declare that what I claim is:

1. In a peat cutting and treating machine, in combination, a vertical tube, a hollow shaft therein carrying a conveyer screw, a shaft extending through said hollow shaft, both of said shafts being vertical, the lower end of said second shaft extending below

the lower end of said first shaft, a screw-like cutting device carried by the lower end of said second shaft to cut the peat and to deliver it into said tube, said cutting device consisting of a truncated conical member having a plurality of helical passages therethrough, and having cutters at the lower edges of said openings, a motor, and gearing operatively connecting said motor with said shafts whereby the latter are driven by the former.

2. In a peat cutting and treating machine, in combination, a vertical tube, a hollow shaft therein carrying a conveyer screw, a shaft extending through said hollow shaft, both of said shafts being vertical, the lower end of said second shaft extending below the lower end of said first shaft, a screw-like cutting device carried by the lower end of said second shaft to cut the peat and to deliver it into said tube, said cutting device consisting of a truncated conical member having a plurality of helical passages therethrough, and having cutters at the lower edges of said openings, said cutters extending beyond the lower piece of said member, said member carrying a drill to facilitate the vertical movement of the cutting device, a motor, and gearing operatively connecting said motor with said shafts whereby the latter are driven by the former.

In testimony whereof I have signed my name to this specification in the presence of two subscribing witnesses.

CONSTANTINE ZELENAY.
